UNITED STATES PATENT OFFICE.

THOMAS J. MERRYMAN AND CARL L. ALLEN, OF LINCOLN, NEBRASKA.

TELEPHONE.

No. 823,886.

Specification of Letters Patent.

Patented June 19, 1906.

Application filed August 25, 1904; Serial No. 222,044.

To all whom it may concern:

Be it known that we, THOMAS J. MERRYMAN and CARL L. ALLEN, citizens of the United States, residing at Lincoln, in the county of Lancaster and State of Nebraska, have invented cert in new and useful Improvements in Telephones, of which the following is a specification:

This invention relates to telephones.

The object of the invention is to provide a novel form of lighting attachment for use in connection with telephones and disposed in such relation thereto as to furnish an effective light in a prescribed zone and without discomfort to the user to enable him to consult the telephone-directory or otherwise employ the light in the use of the instrument.

With the above and other objects in view, it will appear as the nature of the invention is better understood, the same consists in the novel construction and combination of parts of a telephone lighting system, as will be hereinafter fully described and claimed.

In the accompanying drawings, forming a part of the specification, and in which like characters of reference indicate corresponding parts, Figure 1 is front elevation of a telephone with the improvements of the present invention applied thereto. Fig. 2 is a detailed view of the lamp and its bracket. Fig. 3 is a diagrammatic view of the lamp and transmitter circuits. Fig. 4 is a detail view of the transmitter of a desk-telephone, showing the invention in a modified form applied thereto. Fig. 5 is an interior view of Fig. 4, showing the lamp-circuit and switch for controlling the same.

Referring to the drawings, 1 designates generally the telephone-box, 2 the transmitter, and 3 the receiver. As these parts may be of the usual or any well-known construction, detailed description thereof is deemed unnecessary.

The present invention resides in a novel form of lamp and means for controlling the passage of a current thereto.

The lamp comprises a bracket 4 and an incandescent electric lamp 5, detachably combined therewith. The bracket may be made of any suitable material and is provided with a base 6 to be attached to the door of the telephone-box and with a concaved deflector 7 disposed at right angles to the neck 8 of the bracket and having its under or con-

caved surface burnished or polished to present an efficient means for reflecting the light-rays. The reflector forms the support for the lamp 5, the disposition of which is such as to be effectively shielded from the eyes of the user of the instrument, and thereby avoid any discomfort in use.

The current is supplied to the lamp from the telephone-cells 9, the arrangement of the transmitter and lamp circuits being shown in Fig. 3. The transmitter-circuits include a series of cells 9, from the terminals of which lead wires 10, connecting with binding-posts 11. In electrical connection with these posts, are two spring-contacts 12, which normally engage posts 13, with which connect the wires 14, including the transmitter 2, the circuit formed by the wires 10 and 14 and posts 11 and 13 being normally closed. Adjacent to the posts 13 are similar posts 15, with which connect the wires 16, leading to the lamp 5. In order to switch the current to the lamp when desired, a push-rod 17 is provided, which projects beyond the side of the telephone-box and is operatively connected with, but insulated from, the contacts 12, the bar being provided with an offset 18 to engage with the wall of the box to hold it against movement from the stress of the contacts. When this rod is pushed in the appropriate direction, it deflects the contacts 12 and causes them to leave the posts 13, thereby opening the circuit through the transmitter and by engagement with the posts 15 closing the circuit through the lamp and causing the same to glow. As soon as the rod is moved to its normal position the circuit through the transmitter is restored.

In the arrangement shown in Figs. 4 and 5 the lamp-bracket is employed in lieu of the push-bar to open and close the lamp-circuit. This is effected by providing the cylinder or head 19 of the desk-telephone with aligned guides 20 to be engaged by lateral offsets 21, formed of the base of the bracket 22, which otherwise corresponds in all essential particulars with that shown in Fig. 1. On the inside of the cylinder is a spring-contact 23 in normal contact with posts 24 25, with the former of which connects the battery-wire 26. With the post 25 connects a wire 27, leading to the transmitter. (Not shown.) Adjacent to the post 25 is a post 28, with which connects a wire 29, (shown in dotted

lines in Fig. 4,) connecting with the lamp, the return from the lamp to the battery being through bracket, cylinder, and telephone-box. Connecting with the contact 23 is a button 30, which projects above the cylinder 19 and has its shank disposed in a slot 31 therein. When a light is desired, the bracket is drawn outward beyond the cylinder-head, as indicated by dotted lines, and the button 30 is shifted to bring the contact 23 into engagement with the post 28, thus closing the circuit and lighting the lamp. A reverse movement of the bracket opens the lamp-circuit and closes the transmitter-circuit.

15 It would be obvious that the same movement of the bracket which closes the lamp-circuit also brings the lamp into proper position to illuminate effectually the station-selecting means, while the reverse movement 20 which opens the lamp-circuit carries the lamp into a position where it is not liable to be broken.

As shown in Fig. 1, the lamp is combined with a telephone equipped with a selecting device having a novel form of dial 32. The selecting mechanism and dial forms no part of the present invention and is not, therefore, described; but the dial is of peculiar advantage and will be included herein.

30 Having thus described the invention, what is claimed, and desired to be secured by Letters Patent, is—

1. In a telephone lighting system, the combination of a telephone instrument having a transmitter, a receiver, and a hook for the latter, a transmitter-circuit, including a resilient contact and a binding-post against

which the resilient contact normally rests, a lamp-circuit having a terminal secured to a binding-post disposed adjacent to that of the transmitter-circuit, a source of electrical energy for the circuits, and a slidable device mounted in the instrument and connected to the contact and arranged when moved to cause said contact to engage the binding-post of the lamp-circuit.

2. In a telephone lighting system, a transmitter-circuit, including resilient contacts and binding-posts with which the contacts normally engage, a lamp-circuit having its terminals secured to binding-posts disposed adjacent to those of the transmitter-circuit, a source of electrical energy for the circuits and means for flexing the contacts to cause them to engage the binding-posts of the lamp-circuit, thus to open the transmitter-circuit and close the lamp-circuit.

3. In a telephone lighting system, a transmitter-circuit including resilient contacts and binding-posts with which the contacts normally engage, a lamp-circuit having its terminals secured to binding-posts disposed adjacent to those of the transmitter-circuit, a source of electrical energy for the circuits and a push-bar for actuating the contacts to open the transmitter-circuit and close the lamp-circuit.

In testimony whereof we affix our signatures in presence of two witnesses.

THOMAS J. MERRYMAN.
CARL L. ALLEN.
